CURTAIN SUPPORTING AND OPERATING
MECHANISM

Chester Rakeman, New York, N. Y.

Application February 5, 1948, Serial No. 6,483

13 Claims. (Cl. 160—346)

1

This invention relates to curtain supporting and operating mechanisms. Although designed and intended for use in connection with stage curtains, the invention is not limited thereto but is generally adapted to curtains, draperies and the like.

Mechanisms of this type usually comprise a supporting track or tracks having a draw-line associated therewith and curtain supporting carriages movable therealong. In order to draw the curtain in unfolded condition across the proscenium or other space to be curtained, and at the same time to provide for gathering the curtain for support in folded condition when drawn aside, the supporting carriages embody devices for gripping the draw-line at spaced intervals when moving across such space and for automatically releasing the draw-line to permit the supporting carriages' moving into abutting relation to fold the curtain when drawn aside. The gripping mechanisms permit drawing the curtain without subjecting the material thereof to the stresses produced by the drawing operation.

An object of this invention is to provide a curtain supporting carriage having an improved construction and arrangement of draw-line gripping mechanism adapted to be operated to release or grip the line at predetermined points in the carriage travel along the supporting track.

A further object is to provide a curtain supporting and operating mechanism constructed and arranged to permit operation of a one-piece curtain to completely curtain the associated space in unfolded arrangement, and to provide for withdrawal thereof to either side or alternately to opposite sides in folded condition.

A further object is to provide a curtain operating mechanism having an improved curtain supporting carriage.

A still further object is to provide an improved curtain mechanism constructed and arranged to be equally adapted to single or multiple curtain operation.

Other objects will appear from the following description of an illustrative embodiment of the invention taken together with the attached drawing, in which Fig. 1 is an elevation, partly broken away, showing the curtain supporting track and the operation of the carriages in supporting the curtain in folded condition when drawn aside, while supporting it in unfolded condition for movement across the space to be curtained. Fig. 2 is a vertical sectional view, partly in elevation, illustrating the improved carriage construction of the present invention and the arrangement and operation of the draw-line gripping mechanism.

2

Figs. 3 and 4 are sections on the lines 3—3 and 4—4 of Fig. 2.

In the present invention a curtain supporting track is formed by an inverted U-shaped member 11 having a carriage supporting surface 5 formed by a pair of inwardly extending flanges 12 projecting inwardly from each arm of the U-shaped member and arranged to provide a space therebetween. The track is, as usual, mounted to extend across the space to be curtained, such, for example, as a stage proscenium. The inner face 13 of the web 14 of the U-shaped member constitutes a cam surface for controlling the operation of the line gripping means on the curtain supporting carriages as hereinafter described. A draw-line 15 is located below the track for movement in either direction longitudinally of the track.

A plurality of curtain supporting carriages 16 are mounted on rollers 17 which support the carriage for movement on the track flanges 12. Each carriage has a curtain supporting hanger 18 provided with an elongated eye or bore 19 through which the draw-line runs and the curtain 21 is connected by hooks 22 to the lower end of the hangers 18.

Each carriage is provided with a line gripping jaw 23 which may have a serrated face 24, if desired, to increase its frictional gripping of the line 15. Each jaw is mounted for vertical movement into and out of operative line gripping position in which it cooperates with the bottom face of the eye or bore 19, which forms a second jaw, to grip the draw-line 15 and cause the carriage 16 to be moved along the supporting track by the draw-line. Each movable jaw 23 is formed at the lower end of a stem 25 extending upwardly through a bore or socket 26 formed in each carriage 16 to a position adjacent the cam surface 13. Each stem is provided with a cross-head 27

30 on which are mounted a pair of cam surface engaging rollers 28 which ride along the cam surface 13 as the carriage moves along the track. A helical spring 29 surrounds each stem 25 in the associated bore and bears at its upper end against 40 a spring seat 31 adjacent the cross-head 27. This spring maintains the jaw operating rollers 28 in engagement with the cam surface 13 and insures release of the draw-line 15 when such cam surface permits.

50 It will be apparent that a plurality of carriages 16 are employed and are connected to the curtain 21 at suitably spaced intervals by the hooks 22. Two lead carriages 32 are provided, which form the terminal carriage at each end of the curtain. 55 These terminal or end carriages preferably have

double hangers 18' and dual movable jaws 23', as best shown in Figs. 2 and 4. The jaws 23' of the terminal carriages are similar to the jaws of the other carriages and are adapted to grip and release the draw-line 15 in the same way. The web 14 of the U-shaped track member is provided with an inclined section 34 located in the track member at each side of the space to be curtained, and each incline 34 is spaced from the associated end of the track a distance sufficient to leave room between the incline and the end of the track for the gathering and supporting of the curtain in folded condition when drawn aside.

It will be apparent that the invention is adapted for use with a two-piece curtain in which separate curtains are drawn inwardly from each side of the space to be curtained to meet or overlap at the center thereof, or it may be employed with a single curtain adapted to be drawn across the entire space from one side and to be withdrawn alternately to opposite sides, or to one side, only, according to choice.

Assuming, for example, that a single curtain, as shown in Fig. 1, is to be used, movement of the draw-line 15 to the right draws the curtain toward the right end of the track. As the lead carriage 32 passes the incline 34 of the jaw-operating cam surface 13 moving to the right, the jaws 23' of the lead carriage are raised by the associated springs 29 to release the draw-line 15. This permits the succeeding carriage 16 to be drawn into abutment with the lead carriage 32, and the gripping jaw 23 of the succeeding carriage 16 likewise releases the draw-line 15. In a similar manner each succeeding carriage 16 moves into abutment with the preceding carriage and releases the draw-line 15 as it passes the inclined surface 34 with the result that the curtain 21 is gathered and supported in folded condition as illustrated at the right of Fig. 1. It is to be noted that the operation of the draw-line 15 is discontinued before the terminal or lead carriage 32 at the opposite edge of the curtain 21 reaches the inclined cam surface 34 with the result that the jaws 23' on the left-hand lead carriage 32 retain their grip on the draw-line 15 so that when the latter is next moved to the left the left-hand lead carriage 32 moves with it, causing the adjacent fold in the curtain 21 to unfold and draw the next carriage 16 along the track past the incline 34, moving to the left across the space to be curtained. As each succeeding carriage 16 moves to the left past the incline 34, the associated jaw is pressed into gripping engagement with the draw-line 15. Obviously, the curtain is thus drawn across the space in unfolded condition to curtain such space, the draw-line, of course, being manipulated so as to discontinue its movement when the space is curtained. Subsequent operation of the draw-line to draw the curtain aside can be accomplished by moving it in either direction, and the curtain can be drawn into folded condition at either end of the supporting track 11.

It will be obvious that when dual curtains are employed, a pair of supporting tracks can be used extending inwardly across the open space from each side and, if desired, the ends of the tracks can project past each other to permit overlapping of the dual curtains in closed position. With such a construction, of course, the two curtains are always opened by moving to their respective sides.

Having described an illustrative embodiment of the invention, it is pointed out that various changes and modifications may be made therein

without departing from the invention as set forth in the following claims.

What is claimed is:

1. A curtain operating mechanism comprising in combination, an inverted U shaped track having dual surfaces adapted to extend across the space to be curtained, one of said surfaces having an inclined cam section adjacent the respective ends of the track a draw-line movable along said track, a carriage supported on one of said surfaces for movement therealong and including a curtain supporting hanger having an eye through which said line runs, a reciprocable clamping jaw vertically movable relatively to said eye and cooperating therewith to grip said line, and movable means associated with said other surface of the track adapted to follow the other surface and the inclined cam section for actuating said jaw to grip and release said line at determinate points in the travel of said carriage.

2. A mechanism comprising in combination, a hollow track having dual surfaces adapted to extend across the space to be curtained, one of said surfaces being inclined adjacent the ends of the track to form a cam thereat a draw-line movable along said track, a carriage supported on one of said surfaces for movement therealong and including a curtain supporting hanger having an eye through which said line runs, a reciprocable clamping jaw extending through the carriage and movable relatively to said eye and cooperating therewith to grip said line, rotatable means disposed above the carriage and in connection with the jaw movable along said other surface for actuating said jaw to grip said line at determinate points in the travel of said carriage on the track and tensioned means for yieldingly maintaining said jaw actuating means in engagement with said other surface to release said draw-line when said carriage reaches a predetermined cam point adjacent the end of said track.

3. A mechanism comprising in combination, an inverted U shaped track having dual surfaces adapted to extend across the space to be curtained, a draw-line movable along said track, a carriage having roller means supported on one of said surfaces for movement therealong, said carriage including a depending curtain supporting hanger having an eye through which said line runs, a slidably mounted reciprocable clamping jaw in the carriage movable relatively to said eye and cooperating therewith to grip said line, roller means connected to said jaw and movable along said other surface for actuating said jaw to grip said line at determinate points in the travel of said carriage, said track having an inclined top surface for actuating said jaw when the roller means are abutting said top, and spring means intermediate the hanger and the roller means for yieldingly maintaining said roller in engagement with said other surface to release said draw-line when said carriage reaches a predetermined point adjacent the end of said track.

4. A curtain supporting and operating mechanism comprising in combination, a track having dual surfaces adapted to extend across the space to be curtained, part of said track having a top inclined surface, a draw-line movable in opposite directions adjacent said track, a plurality of carriages supported on one of said surfaces for movement therealong including an end carriage, a curtain supporting hanger depending from said end carriage adapted to be connected to and support the vertical edge of a curtain, curtain supporting hangers on said other carriages, each of 75 said hangers having an eye through which said

draw-line runs, a spring-pressed slidably mounted clamping jaw mounted on each of said carriages including said end carriage, each extending from the carriages into the associated eye and adapted to cooperate with the associated eye to grip said line, roller means associated with each of said jaws and movable along said other surface and following the contour thereof for actuating said jaws to grip said line at determinate points in the travel of said carriages, whereby the clamping jaw moves up and down relatively of the hangers, said upper surface having an inclined portion as to cause each of said carriages including said end carriage to grip said line during movement of said carriages across the space to be curtained and to release said line at a predetermined point at each side of said space adjacent the ends of said track to permit folding of said curtain when drawn aside at either end of said track.

5. A mechanism comprising in combination, an inverted U track having a straight supporting and a top cam surface adapted to extend across the space to be curtained, a draw-line movable longitudinally of said track, a carriage supported for movement along said supporting surface, a curtain supporting hanger on said carriage including line-gripping jaws, a spring-pressed stem extending through said carriage from the track into the hanger for operating said jaws, and movable means in connection with the stem, engageable with said cam surface for moving said stem to actuate said jaws at predetermined points in the movement of said carriage along said supporting surface.

6. A mechanism comprising in combination, a track having separate supporting and a top inclined surface adapted to extend across the space to be curtained, a draw-line movable longitudinally of said track, a carriage supported for movement along said supporting surface, a curtain supporting hanger on said carriage including line gripping jaws, a spring-pressed stem extending through said carriage from the track into the hanger for operating said jaws, rotatable means engageable with said inclined surface connected to said stem, and cam faces on said top surface so located as to cause the rotatable means to follow the contour of the top surface and operate said jaws to grip said line during movement of said carriage in either direction across said space to be curtained and to release said line at either side of said space.

7. A supporting and operating mechanism for a one-piece curtain comprising in combination, a supporting track adapted to extend entirely across the space to be curtained and beyond each side thereof, a draw-line movable in opposite directions for drawing said curtain from either side of said space to the other, part of said track having a top inclined surface, curtain supporting carriages movable horizontally, along said track, tensioned, vertically movable line gripping means extending from each carriage free of the track, inclined surface means located on said track on opposite sides of said space adapted to actuate said gripping means at the beginning of each carriage movement across said space to grip said draw-line, and to release said line at the other end of the carriage movement at the opposite side of said space, whereby said curtain can be moved from folded position at one side of said space along said track in unfolded condition and into folded position at the other side of said space.

8. A curtaining supporting and operating

75

mechanism comprising in combination, a track adapted to extend across a space to be curtained, a draw-line movable longitudinally of said track, a curtain supporting carriage mounted for movement along said track, and having an opening therein for said line, a slidably mounted spring-pressed line-gripping jaw movably supported on said carriage for movement into and out of operative line gripping position in the opening of said carriage rotatable means in connection with the jaw adapted to follow the contour of the track for operating said jaw to grip said line during movement of said carriage in either direction across said track, and inclined cam surface means on said track forming part of the opposite ends of the track to release said line when said carriage reaches either side of said track.

9. A curtain carrying and operating mechanism comprising in combination, an inverted U track having a curtain supporting surface adapted to extend across a space to be curtained, a top inclined surface operatively associated with said supporting surface, a draw-line movable longitudinally of said supporting surface, a carriage movable along said supporting surface, a curtain supporting hanger on said carriage projecting below said surface and having an eye through which said draw-line runs, a line clamping jaw in connection with the carriage movable relatively to said eye and cooperating therewith to grip said line, a reciprocable jaw-supporting stem extending through said carriage and having one end operatively associated with said top inclined surface, roller means in connection with the stem, and tensioned means around the stem for yieldingly holding said stem in operative association with said top inclined surface and to release said jaw at a predetermined point in the travel of said carriage on the track when the roller means engages the top inclined surface.

10. A mechanism comprising in combination, a track having a curtain supporting surface adapted to extend across a space to be curtained, a top inclined surface operatively associated with said supporting surface, a draw-line movable longitudinally of said supporting surface, a carriage movable along said supporting surface of the track and having a curtain supporting hanger projecting below said surface provided with an eye through which said draw-line runs, a line clamping jaw movable relatively to said eye and cooperating therewith to grip said line, a jaw operating stem extending through a socket formed in said carriage to a position adjacent said cam surface, rotatable means carrying the stem, and spring means in the carriage associated with said stem and located in said carriage socket for maintaining said rotatable means in operative contact with said top surface and to release said line at a predetermined point in the travel of said carriage.

11. A curtain supporting and operating mechanism comprising in combination, a track formed by an inverted U-shaped member having spaced lower supporting surfaces and an upper inclined cam surface and a relatively straight top surface, a draw-line movable longitudinally of said track and spaced below said supporting surfaces, a curtain supporting carriage having spaced rollers mounted on and movable along said supporting surfaces and a curtain supporting hanger mounted on said carriage and projecting downwardly through the space between said supporting surfaces, said hanger having an eye through which said draw-line runs, a line gripping jaw

movably supported in said eye and cooperating with said eye for gripping said line, a jaw operating stem extending through said carriage, stem operating rollers mounted thereon and movable along said cam and straight top surface, and means for yieldingly holding said rollers in contact with said cam and straight top surfaces and relatively moving said jaw in and out of line gripping position.

12. A curtain mechanism comprising in combination, an inverted U-shaped track member having spaced inner surfaces formed by inwardly extending flanges on each arm of the U-shaped member and a web and inclined surface above said inner surfaces, a carriage movable along said supporting surfaces, a curtain supporting hanger on said carriage projecting downwardly through the space between said flanges and having an eye, a draw-line running through said eye and movable longitudinally of said track, line gripping means reciprocable within said eye to connect said carriage to said line for movement therewith, a vertically movable spring-pressed plunger slidably mounted in a bore extending through said carriage for operating said gripping means, means on said plunger engaging the top of said U-shaped member adapted to follow the contour thereof, and a top inclined surface on said inner face for actuating said plunger to operate said line gripping means at predetermined points in the movement of said carriage along said track.

13. A mechanism comprising in combination, an inverted U-shaped track member having spaced inner supporting surfaces formed by inwardly extending flanges on each arm of the
